ASSIGNORS, BY MESNE ASSIGNMENTS, TO GENERAL STEEL CASTINGS CORPORATION,
OF GRANITE CITY, ILLINOIS, A CORPORATION OF DELAWARE

RAILWAY CAR

Original application filed April 8, 1929, Serial No. 353,494. Divided and this application filed July 15, 1931.
Serial No. 550,937.

The invention relates to railway freight cars and particularly that class of equipment known as "hopper cars" wherein the lower portion of the car body comprises a plurality of hoppers. These hoppers are disposed on the opposite sides of the center construction of the car and cross bearers are positioned between adjacent hoppers which are secured to the opposite side walls of the car and also connected to the center construction. Some cars have just one cross bearer, while others have a plurality of cross bearers with hoppers disposed on both sides thereof. Other railway dump cars do not have any cross bearers but have a relatively long longitudinally extending door on each side of the center construction. There are other numerous types of railway hopper cars which need not be enumerated here and to which this invention will apply.

In such type of cars the moisture in the lading, due to rain, melting snow, thawing of the material, etc., accumulates adjacent the bottom part of the lading so that that part of the lading in contact with the hoppers, center construction, cross bearers and other associated parts becomes wet and holds the moisture in contact therewith causing excessive corrosion when these parts are made of rolled steel, especially if such rolled steel parts have been deformed by pressing. It is common practice to use such doors for transporting coal and when moist coal, particularly coal dust, is allowed to remain in contact with the rolled steel parts, the acid formed thereby eats into the steel parts.

Such corrosive and acidic action rapidly eats away the rolled steel and experience shows that these hoppers and associated parts must frequently be replaced, which is expensive, not only from material and labor cost, but also by keeping the car out of service.

An object is to eliminate the cost and delay in fabricating the numerous component parts of the present structural steel car parts.

Another object of forming the car part of cast metal is to eliminate the possibility of loose connections which would permit relative motion between the component parts of the car part, as it is common knowledge that

the vibration of the car in motion, due to rough and uneven track, and steel wheels rolling on steel rails, together with longer trains and high speeds in present day practice, cause riveted joints and built-up sections to work loose and the railroads look with favor upon any device which reduces the number of parts and joints as these are the weak parts of the car and the more such weak parts are eliminated, the longer the life of the car.

An object of the invention is to form the parts of the car which come in contact with the lower part of the lading of cast metal to eliminate corrosion and acidic action.

In the drawing:

Fig. 1 is a cross section of a car including my improvement.

Fig. 2 is a fragmentary side elevation of the car.

Fig. 3 is a fragmentary longitudinal section of the car.

In a "hopper car" of the type described above the load is carried to the body bolsters 2 by the center construction 4 and the side walls 5. The center construction usually comprises spaced apart center sills 3 of rolled steel sections and a rolled steel cover plate 6, which sills and cover plate extend between the body bolster and usually therebeyond to accommodate the draft gear. The side walls may be of a truss or a girder design. In the form illustrated the top (7) and bottom (8) chords of the side girder are connected by the web plate 9 which also is the load retaining means of the side wall. To meet strength requirements it is preferable to make the top and bottom chords of rolled steel. In order to save weight and material it is desirable to make the web plate also of rolled steel.

The car illustrated includes an integral casting comprising a hopper on each side of the center construction, a center construction hood and part of a cross bearer. Two of such castings (preferably duplicates) are secured together to form the complete hopper part of the car, which united castings are then merely secured to the center construction and opposite side walls of the car. Each part of the cross bearer comprises a web plate 13 with

the upper stiffener 14 and oppositely disposed sloping lower portions 15 which direct the discharging lading into the hopper. The cross bearer is arranged to protect the lower 5 side chord 8 and the lower portion of the web plate 9 from the lading. The cross bearers straddle the center construction 4 and are secured thereto in any convenient manner. We also prefer to cast hinge lugs 16 integral 10 with this cross bearer to support the hopper door 17. The brace is secured to the side wall and also to the outer end of the cross bearer 12 and comprises a diagonal member 18 extending from adjacent the top of the side 15 wall to substantially the middle of the cross bearers. It is also provided with an extension 19 connected to the upper chord 7 to brace that member against deflection. The hoppers 20 on opposite sides of the cross 20 bearer are preferably cast integral therewith. These hoppers comprise an inclined portion 21 with oppositely disposed substantially upright portions. The inner (22) of said upright portions is connected to the center sill 25 and arranged to protect it from the lading. The outer (23) of said portions is connected to the side wall and arranged to protect the lower chord (8) from the lading. The integral reinforcing ribs 24 extend continuously 30 around the inclined portion and the upright portions of the hopper. The hopper is also preferably reinforced with longitudinally extending integral ribs 25 below the inclined portion.

35 The accompanying drawing illustrates the preferred form of the invention, though it is to be understood that the invention is not limited to the exact details of construction shown and described, as it is obvious that various modifications thereof, within the scope 40 of the claims, will occur to persons skilled in the art.

This is a division of our co-pending application No. 353,494, filed April 8, 1929.

45 We claim:

1. In a railway car, the combination of a center sill, a side wall, a cross bearer extending between and secured directly to the center sill and the side wall, said cross bearer 50 formed of a pair of members secured together, each consisting of an integral casting comprising a vertical web, a downwardly sloping portion extending from said web, and an upper stiffening flange.

55 2. In a railway car, the combination of a center sill, a side wall, a cross bearer extending between and secured to the center sill and the side wall, said cross bearer formed of a pair of members secured together, each 60 consisting of an integral casting comprising a vertical web, a downwardly sloping portion extending from said web formed with hinge lugs, and an upper stiffening flange.

65 3. In a railway car, the combination of a center sill, a side wall, a cross bearer extend-

ing between and secured to the center sill and the side wall, said cross bearer formed of a pair of members secured together, each 70 consisting of an integral casting comprising a vertical web, a downwardly sloping portion extending from said web, and an upper stiffening flange having an outwardly and downwardly inclined upper surface.

4. In a railway car, the combination of a center sill, a side wall, a cross bearer extending between and secured to the center sill and the side wall, said cross bearer formed of a pair of members secured together, each 75 consisting of an integral casting comprising a vertical web secured to the web of the other member, a downwardly sloping portion extending from said web, and hopper side walls 80 extending longitudinally of the car.

5. In a railway car, the combination of a center sill, a side wall, a cross bearer extending between and secured to the center sill and the side wall, said cross bearer formed of a pair of members secured together, each 85 consisting of an integral casting comprising a vertical web secured to the web of the other member, a downwardly sloping portion extending from said web formed with hinge lugs, and an upper stiffening flange having an outwardly and downwardly inclined upper surface.

90 6. In a railway car, the combination of a center sill, a side wall, a cross bearer extending between and secured to the center sill and the side wall, said cross bearer formed of a pair of members secured together, each 95 consisting of an integral casting comprising a vertical web secured to the web of the other member, a downwardly sloping portion extending from said web, an upper stiffening flange, and substantially vertical webs 100 extending between said portion and said flange.

105 7. In a railway car, the combination of a cross bearer for a railway car formed of a pair of members secured together, each consisting of an integral casting comprising a vertical web, a downwardly sloping portion extending from said web, an upper stiffening flange and hopper side walls.

110 8. A cast metal device comprising a railway car hopper with an integral inclined web 115 arranged for cooperation with a contiguous device to form a rigid structure including an angular cross bearer.

120 9. A cast metal device comprising a railway car hopper with integral projections forming a center sill hood and an inclined web adapted to be united with a similar web of an adjacent device to form an angular cross bearer.

125 10. A cast metal device comprising a railway car hopper with an inclined web at one end projecting upwardly to form a sloping end floor and an inclined web at the other end sloping upwardly to form an element of an angular cross bearer.

11. A cast metal device comprising a pair of railway car hoppers, a hood between them for straddling a car center sill, and a continuous inclined web extending transversely of said hood and arranged for attachment to a similar web of an adjacent device to form an angular cross bearer.

12. A cast metal device comprising a pair of railway car hoppers, a hood between them for straddling a car center sill, and a continuous inclined web extending transversely of said hood at one end of the device to form a sloping end floor extending above the hoppers and an inclined web extending transversely at the other end of the device for attachment to a corresponding web of an adjacent device to form an angular cross bearer.
